ORIFICE ELEMENT AND SYSTEM AND APPARATUS UTILIZING THE SAME.

Application filed June 13, 1925. Serial No. 36,928.

This invention is a novel orifice element and system and apparatuses utilizing the same. The novel orifice element and system of orifices to be described, are adapted to a wide field of practical application, and the characteristic features are claimed irrespective of any particular utilization. In describing the invention various methods and apparatuses employing the orifice element and system will be described, and each of these per se is also claimed as novel, in some cases irrespective of the particular characteristics of the orifice element or system itself. In describing particular uses or embodiments of the present invention it is not intended to limit the same to such uses and embodiments, as the general features can readily be employed or developed for an extended variety of uses. Among the various practical employments of the invention, having reference to flow of fluids, including liquids, gases and vapors, are the following: vapor traps, for example to remove liquid from vapor, such as removing water from steam; fluid meters, by which the rate of flow of any fluid is measured, enabling also a determination of the quantity of flow; pressure reducers, for taking down and controlling pressures to or below a desired degree of pressure; fluid feeders, for example for feeding water or other liquid to a boiler or other vessel; fluid mixers, by which two or more fluids from separate points are commingled and delivered for various purposes; fluid distributors, by which flow through a main is subdivided and proportioned to separate points of delivery; fluid ejectors; mufflers, etc.

In the accompanying drawings, showing a number of embodiments of the present invention the figures are more or less diagrammatic, and all of them may be considered as elevation views, in many cases partly broken away or in section to indicate interior construction.

Fig. 1 shows an embodiment of this invention, adapted to serve as a vapor trap, for example for removing water from steam; the same built up from a combination of orifice elements constituting an orifice system embodying the present invention, and illustrating the system of combining such elements with each other and with other pieces of apparatus, and illustrating as well a novel

method and trap for removing liquid from vapor. Fig. 2 is a detail view showing a preferred detail of arrangement, namely with graded sizes of orifice nozzles, as employed in Fig. 1. Fig. 3 is a modification showing in tandem a system of orifice elements of different design from those shown in Fig. 1. Fig. 4 shows a steam or vapor trap of different design from that in Fig. 1. Fig. 5, on a smaller scale, shows the same elements as in Fig. 4, with further connected elements.

Fig. 6 shows an embodiment of the present invention applied to fluid meters, adapted for determining, controlling or measuring the rate or quantity of flow of various fluids, such as steam. Fig. 7 indicates a different form of fluid meter embodying this invention. Fig. 8 shows a still further form of fluid meter embodying the present invention.

Fig. 9 shows a pressure reducing system, operating also as a muffler, constructed in accordance with the present invention. Fig. 10 shows a different particular embodiment, as will be described.

Referring in detail to the constructions shown in the drawings, Fig. 1 indicates a simple form of steam or vapor trap. The pipe 11 may be drawn from the lower side of any passage or chamber containing steam or vapor from which it is desired to remove water or condensed vapor. This pipe is threaded and has connected to its lower end the apparatus constituting the present invention. A series or system of units or elements 12, which I term orifice elements, are interconnected with each other and attached at the lower end of pipe 11. The orifice elements are shown connected in succession or tandem, and it is a feature of this invention that these may be in the form of identical units, connectible in various ways and combinations, with each other and other apparatus. Four orifice units 12 are shown in Fig. 1, connected in tandem, the top one connected to the pipe 11.

Each element 12 consists of a main or chamber wall 13, shown of a bulging or pear shape, an advantageous design for the present purposes, and formed with a threaded entrance portion 14 engageable with the threads of the pipe 11. For convenience the upper or entrance end of the unit 12 may be formed with a flange or bead 15, shown as

a hexagonal bead, facilitating the assembling and disassembling of the apparatus. The lower or exit end 16 of the unit 12 is shown threaded both exteriorly and interiorly. The exterior threads are engageable with the interior threads of the entrance 14 of an identical unit. The interior threads at the exit are adapted to receive an orifice piece or nozzle 17, suitably threaded. Such orifice nozzle is preferably removable and interchangeable with others having orifices of different size or character. Thus as shown in Fig. 2 the several units 12 may be provided with orifice nozzles of progressively increasing aperture at the throat 18. The nozzles may take different forms, for example there may be a tapered approach 19 to the throat, and a flaring getaway 20. To lend greater flexibility of use to the units 12 each of them 15 may be formed with a tapped boss 21 in the chamber wall, for connection to a gage or other apparatus. The top unit 12 is shown with the boss 21 closed by a plug 22, and this is true of the others, with the exception of one of the intermediate units, which may be advantageously connected, by a pigtail siphon or other connection 30, with a pressure gage or indicator 31. The threaded lower exit of the final or bottom unit 12 20 may be connected as shown by a usual form of threaded fitting or coupling 23 to a pipe 24 leading to any desired point, or to waste. The described assemblage affords a simple and positive trapping device. The water 35 present is completely discharged at the final or lowest exit, after accumulating in each unit and being forced through the successive nozzles. Only a minor or a negligible amount of steam is permitted to escape at 40 times when there is no water present. The discharges from unit to unit are at successively decreasing stages of pressure, from the initial pressure in pipe 11 to the final discharge pressure. At each stage the pressure drop is only a fraction of the entire drop, and the orifices effectively discharge 45 any accumulated water, while effectively controlling and limiting the amount of steam passed through from unit to unit. 50 Owing to the progressively lower pressures in the successive units re-evaporation of the progressing liquid readily takes place, and the use of a plurality of units in tandem affords maximum re-evaporation of the liquid being discharged. In this way clean 55 low-pressure steam may be finally delivered from the trap, which may be available for heating or other purposes. The operation is automatic and self adjusting to changes of conditions, and removal of water is completely effected. Compared with steam traps heretofore known the described trap is further superior in that no moving parts or 60 adjustments are required. The apparatus is low of cost, and readily assembled, attached

and used, and repair costs are substantially eliminated.

The most advantageous number and size of units, and sizes of the orifices thereof, for any given conditions, are readily determined 70 by consideration of the initial steam pressure, and the expected quantity of water to be discharged. The successive orifices may be of uniform size throughout the system, but it is preferred to arrange them with 75 progressively increasing sizes toward the final discharge, as indicated at 18^a, 18^b and 18^c in Fig. 2. Thereby the first nozzle, controlling the total discharge rate, causes the main drop of pressure in the system, the 80 subsequent nozzles progressively lowering the pressure until the final nozzle discharges into the lowest pressure of the system, which may often be atmospheric pressure.

The purpose of the gage 31 is to indicate 85 the pressure in any chamber between the first and last orifices, for example, as shown, that in the second unit, that is, in the chamber between the first and second orifices. Knowing the intermediate pressure and the 90 initial pressure, and the character of the orifices between, the relative rate of flow through the system is determinable, by formula, or by special calibration of gage.

The orifice element hereof may be described as a hollow structure, or vessel built up if desired but preferably unitary, being constructed preferably of metal, its walls enclosing a chamber, and having at least two openings, the entrance and the exit, provided with means by which the element or unit may be coupled up to similar units or to other apparatus, and an orifice member or nozzle being contained or supported at a suitable point so that fluids passing through the chamber from entrance to exit must traverse the orifice. The nozzle is preferably machined or drilled with a scientifically designed and sized orifice, and, while it might in some cases be integral, is preferably removable and replaceable by other nozzles with orifices of different size or character. While the nozzle might be differently located it may advantageously be within the exit end as shown, thereby permitting the mode 100 of coupling of units in tandem and connection to other apparatus or piping as shown. The orifice member or nozzle may be of different types. Instead of the tapered-flared nozzle, as shown, there may be a simple perforated washer or plate clamped within the unit; or a thimble type orifice member may be driven into a tapered opening in the unit; the first mentioned giving satisfactorily accurate results with a tandem arrangement.

The bulging or pear shape of orifice unit, as in Fig. 1, is advantageous in its increased capacity, better operation, and wider utility, but this is not always necessary as orifice units such as 12^a in Fig. 3 having conical 125

walls 13^a will frequently suffice, these having threaded entrances and exits 15^a and 16^a. Also, while the unit 12 shown in Fig. 1, is provided with a hexagonal bead 15 at the entrance end and a tapped boss 21 at the side, the arrangements may be extensively varied to suit requirements. Thus in Figs. 4 and 5 the unit 12^b is provided with an additional hexagonal bead 35, near the exit end, increasing the facility of assemblage, especially for applying a wrench to units of large size, while the unit 12^c is formed with a large boss 36 at one side for the purpose of providing a second inlet, to which may be connected a unit 12^d analogous to any of those described. The large units or elements shown in Figs. 4 and 5 may approximate 6 3/4 inches long and 5 1/8 inches outside diameter.

The action of the succession or system of orifices, arranged in tandem, with distinct chambers between them, has been indicated, and may be further described as follows, it being understood that the orifice system may either receive from a pressure line or discharge to a suction line. The four orifices in Fig. 1 have three chambers between them, and cause four stages of pressure drop, the flow at each orifice depending on the character of orifice and the pressures above and below it. The units and orifices preferably trend downwardly, so that any water present quickly reaches the orifices and is discharged. The liquid flows onward ahead of the gas and minimizes steam waste. The water will usually be partly or wholly re-evaporated during its passage to the final outgo pipe or discharge, so that much steam is afforded for collateral uses, heating etc.

Successive orifices of uniform area give less satisfactory results than graded areas of increasing size toward the lower pressures. By the latter the successive pressure drops may be substantially equalized. Thus if 42% drop in absolute pressure is desired in passing through each nozzle, the orifice areas may be successively 75% larger, more or less, as roughly indicated in Figs. 2 and 3. This is calculated as follows. 42% drop of absolute pressure means in the ratio of 1 to .58, or a volume increase to $1 \div .58$ or 1.72, an increase of 72%. The successive orifices are therefore 72% larger progressively to take care of the progressively increasing volume of gas. For traps these percentages are satisfactory, and the arrangement tends to pass the same amount of steam or other vapor at each stage if no liquid is present. With an initial steam pressure of 113.4 pounds per square inch, four orifices, of areas .01944; .03345; .05767 and .09943 will discharge steam at atmospheric pressure, assuming no liquid present, at the rate of about 128 pounds per hour. Higher pressures may require additional larger orifices at the low

pressure end, and lower pressures the removal of orifices. For example with 59.6 pounds pressure the final nozzle can be omitted, using only the first three, and the delivery will be about 74 pounds per hour.

In any case the presence of water to be trapped excludes passage of steam, and the system can be calculated to take care of the water under all circumstances while minimizing the waste of steam. The flow of water through the orifice system is of course at a much greater rate, in pounds, than of steam, making the invention very effective as a trap. The pressure gage indicates the conditions, on the following principles. The rate of flow of steam or other gas through an orifice into a pressure not greater than 58% of the initial absolute pressure may be considered as a direct function of the initial absolute pressure, while on the other hand, the rate of flow of water, not hot enough to reevaporate, through an orifice, is a direct function of the square root of the difference in pressures. If then steam only is present in the orifice system and the orifices are properly proportioned, the pressure gage will stand at a definite point, for example 42% of the absolute pressure in the previous stage, which may be the boiler pressure. Therefore the gage standing at this point will indicate the absence of water. On the other hand with only cold water in the system, since the rate of flow must be the same through each stage or chamber, the absolute pressure drop through the successive nozzles will be about in the ratio of 3 to 1. This is calculated from the knowledge that the flow is a function of the square root of the drop of pressure multiplied by the area of the orifice. The orifices increasing progressively in area in the proportion 1 to 1.72, calculation shows that the pressure drop through successive nozzles is as 2.96 to 1, or about 3 to 1. Therefore the initial pressure, assumed as 113.4 pounds, must represent the total cold water pressure drop through four nozzles. The successive drops through the four nozzles are in the ratio of 27 to 9 to 3 to 1, and apportioning the total drop will give successive drops of about 76 then 25 then 9 then 3. With only cold water in the system therefore the successive pressures will be about 113.4 then 37.4 then 12 then 3 then 0; whereas with only gas or steam the successive pressures will be about 113.4 then 59.6 then 28.4 then 10.6 then 0. As stated therefore the pressure gage, applied at any intermediate stage, will indicate the conditions. When a mixture of steam and water is passing through the system, or when the water is hot enough to reevaporate at one or more stages, different intermediate effects are produced, also indicated by the gage.

In any embodiment of this invention the orifice system may be supplemented by a

strainer or means of any sort located in advance of the orifices to exclude from the orifices any scale, fiber, compounds or other sediment or foreign matter, and thus avoid 5 clogging.

Having now described the orifice elements or units, and their action when connected in tandem, and one embodiment, the trap of Fig. 1, I will proceed to describe other illustrative embodiments.

The trap of Figs. 4 and 5 is a special one devised to drain moisture from the exhaust pipe, for example, of a prime mover, and discharge it at some desired point, perhaps 15 at a greater elevation than the source, in cases where the exhaust pressure is itself insufficient, with a simple orifice system, to force the water to the desired point. This embodiment utilizes steam from another 20 point to elevate the exhaust water. A pipe 34 is shown, leading for example from the drip connection of a throttle valve, dispensing with any other trap at that point. This 25 conducts the steam into orifice element 12^a, which is coupled to a special two-entrance element 12^c, the discharge coupling 23 of which leads by pipe 24 to the desired point, for example to a feed water heater. To the 30 second entrance 36 of element 12^c is coupled an element 12^a, containing orifice nozzle 17, and receiving water from the exhaust by down pipe 37, which water is delivered 35 downwardly into element 12^c. The outlet of element 12^c has a special orifice 17^a with 40 greatly elongated flared exit 20^a, extending through element 12^c and into the exit 16 thereof, forming an ejector. This embodiment therefore illustrates not only a special trap but an advantageous built-up ejector, 45 capable of general uses, and available by mere assembling of stock parts.

The steam under pressure delivered 45 through the ejector tube 20^a produces suction in the chamber 12^c, drawing the water 50 therefrom, and lifting it to the desired point. This simple combination therefore serves doubly, first to receive and utilize the water collected at the throttle drip, and second to trap and utilize the waste 55 water from the exhaust, keeping both sets of pipes dry. The apparatus will operate even with moderate vacuum in the exhaust pipes. The combination is believed to be new in principle irrespective of the make-up of structure; thus an ordinary ejector 60 may be used, with connections analogous to those shown, enabling the drip steam from the throttle to be used as a motive power to lift low pressure water or discharge 65 it against pressure, performing the service of a pump as well as two traps. When the drip steam pressure is excessive, additional orifice elements or a valve 38 may be introduced between element 12^c and the source of 70 the steam, to reduce the pressure to the best

for ejector purposes, for example, about 50 pounds. To prevent high pressure entering the exhaust passages a check valve may be introduced adjacent to the element 12^a. The gage 31 assists in conserving the steam 70 from the throttle by indicating the pressure and enabling the flow to be regulated to the needs of the ejector. The exhaust main may be provided with a differential gage 75 for indication purposes.

As already stated, traps such as the vapor traps described, constitute only one instance of utility of the present invention in apparatus wherein fluids at higher pressures are subject to controlled escapement to lower 80 pressures for various purposes, other embodiments having been enumerated. Next will be described the embodiment of the present invention in fluid meters, with the three illustrations shown in Figs. 6, 7 and 8.

The purpose of such meters is to indicate the rate of flow of the fluid (gas, vapor or liquid), the total quantity passing through the meter being determinable from the rate of flow. For ordinary commercial metering 90 purposes the flow is regulated at a point after passing the meter according to variations of demand, the drop in pressure usually being quite small, and a differential pressure gage, such as a U-tube, being desirable. The invention however is also available for a second class of meters, wherein the regulation is either before or after passing the meter, and wherein the drop in absolute pressure is large, for example to 58% 100 or less of the initial pressure; and in this case a differential gage is unnecessary, as a single gage can be employed and calibrated to indicate directly the flow either in volume or weight.

Fig. 6 shows a meter of the first mentioned class, available for ordinary commercial purposes. Where it is desired to maintain the secondary or delivered pressure practically as high as the initial pressure a single orifice is sufficient. The drawing shows a supply pipe 40 leading to a unit 12^c containing an orifice nozzle 17, this unit coupled to a similar unit 12^{ce} which has no orifice nozzle, but is provided with a 110 coupling 41 connecting it with a delivery pipe 42, the regulation of flow being at a point beyond the illustrated elements. The units 12^c and 12^{ce} afford two chambers with the orifice 17 between them, there being a 115 drop in pressure between the chambers in accordance with the rate at which the fluid is drawn from the lower chamber. The tapped boss of the upper chamber has a pipe connection 43 which may be in the form of a 120 pigtail siphon, and the lower chamber a similar connection 44, the two connections extending to a differential gage or indicator 45, the index or pointer of which moves 125 in accordance with the differences in pres-

sures in the two chambers. The rate of flow will vary in proportion to the square root of the pressure difference between the two chambers, this giving a ready mode of determining flow. The dial can be calibrated to indicate either the pressure difference or the resulting rate of flow or both. There are a number of efficient differential pressure gages on the market available for the described purposes, and therefore the details thereof need not herein be described. The combination shown in Fig. 6 is useful for many purposes, examples of which are the measuring of discharge of steam from 15 boilers, the delivery of steam to prime movers, the admission of feed water to boilers, the flow of oil in pipe lines, etc.

An instance of the second mentioned class of meters is shown in Fig. 7, in which the supply pipe 40 leads to a series of three, or more or less, units or chambers 12^t arranged in tandem. Orifice nozzles 17 are shown between each two chambers, thus presenting a tandem arrangement permitting considerable pressure drop between the supply pipe 40 and the delivery pipe 42. A pigtail connection 48 is here taken from the middle chamber, between the orifices, and leads to a pressure gage 49 which may readily be calibrated to indicate the flow in pounds per hour. This apparatus is adapted to meet certain special but frequently encountered conditions, for example to indicate when and how much steam is being used at some remote point, for example by some low pressure process or apparatus. The control of flow therefore is beyond the metering apparatus. When no steam is being drawn at the low pressure end the gage 40 will give an indication corresponding with boiler pressure. When the distant valve is open there will be flow of steam and a pressure drop through each orifice. The gage 45 may be selected and calibrated to indicate directly the rate or weight of flow through the system. For example, with one inch or other size orifices, the pressure in the middle chamber will vary in accordance with the rate of flow, enabling the dial to 50 be calibrated to indicate the rate, for example, giving the number of pounds of steam per hour. The first orifice in this combination is important since without the restriction it affords, the steam pressure will 55 continue up to the second orifice. The first orifice in effect is a variable pressure reducer. Where the initial steam pressure is very high the number of orifices may be increased, for example to three or four in 60 number, giving a considerably reduced delivered pressure, and the pressure reading may be taken from any convenient intermediate chamber.

While the described combination of Fig. 65 7 has been discussed only in connection with

the flow of steam the principles can be used for metering liquids. In that case if two orifice nozzles of the same size are used, the pressure in the chamber between them will be the average of the initial and final pressures. This fact enables a single gage connection, as shown, to be employed for accurate indication of the rate of flow, assuming either a constant initial pressure or a constant final pressure in the liquid. 70

The assemblage shown in Fig. 8 may be used as a fluid metering combination of the second class, and comprises the threaded supply pipe 52 leading from any pressure regulating means, such as an orifice system as already described, or a simple throttle valve 53, preceded by pipe 54. The pipe 52 leads directly into the orifice unit or chamber 12^t containing orifice nozzle 17, and the tapped boss at the side has a connection 55 in the form of a pigtail siphon to a pressure gage 56. An example of the use of this combination is where steam is to be delivered from a high pressure to a receiving vessel in which the pressure is not in excess of 58% of the initial absolute pressure, this condition existing in many processes, notably in oil refining. If constant flow through the orifice is desired the pressure within the unit or chamber should be 95 uniform, and this may be brought about by replacing the throttle valve 53 by an automatic reducing valve, or if the main line steam pressure is constant the throttle valve 100 may serve, or be replaced by an orifice system according to this invention, operating as a pressure reducing device. 100

With the embodiments of Figs. 7 or 8, or similar flow measuring arrangements, when used for measuring dry steam or other elastic fluid, the gage 49 or 56 can be calibrated to show absolute pressure, or about 14.7 lbs. per square inch higher than ordinary gage calibrations (e. g. by setting the pointer ahead 14.7 spaces on the scale), and then 110 such pressure gage, and its pressure graduation marks can be made to indicate directly the rate of flow in pounds per hour by employing an orifice leading from the pressure chamber which has an effective discharge area of approximately .0195 square inch, in the case of steam, or a corresponding area with another fluid, assuming a pressure drop through the orifice to not less than 115 58% of the chamber pressure. The pointer then will indicate not only the absolute pressure, but by the same calibrations and readings will indicate the flow rate in pounds per hour. When greater flow is required the orifice area can be a simple multiple of .0195, e. g. 1.95, in which case the pressure calibrations of the gage show the flow rate by using the same simple multiplier, e. g. 100, upon the pressure indication, and the multiplied readings can be applied to the 120 125 130

same calibration marks used for pressure indication. As the pressure in the orifice chamber varies, this variation will be indicated on the gage as a change of absolute pressure, and this change of gage reading at the same time indicates the change taking place in the rate of steam flow, from which the total flow in any given period of time can be readily figured out. This branch of the present invention however is not made the subject of specific claim herein, but is reserved and is made the subject of a copending application for patent.

Pressure reducing apparatuses are indicated in Figs. 9 and 10. The purpose of such combinations is to take down a high initial pressure in easy stages to or below a designated maximum pressure. For example a boiler pressure of 85 pounds can be reduced so as to deliver not more than 43.13 pounds pressure. The uses are various. One use is as a supplement to an ordinary or automatic reducing valve, the orifice system located either before or after the valve; for example the orifice system can be employed to bring down the pressure approximately to the desired reduced pressure, enabling the automatic valve to give much more accuracy in control of delivered pressure, although the orifice system can be used without the valve.

Fig. 9 shows a threaded pipe 60 leading to the first of the orifice units 12¹. Preceding the pipe 60 is shown a blowoff cock 61, or a safety valve could be substituted, and preceding that a pipe 62 from the steam supply or boiler. Beyond the orifice system is shown a coupling 63 for connecting to the delivery pipe of the system. Two orifices 17 are shown, one in each orifice unit. In this combination the orifice system, acting as a pressure reducer, may serve to remove certain difficulties existing in the use of safety valves. When boiler valves are blown off into atmospheric pressure this causes excessive noise, as well as wear upon the valve, the difficulty being so noticeable that special valve seats and disks have had to be designed in an endeavor to reduce the resulting wear, and the gradual increase of prevailing boiler pressures has accentuated the difficulty. The employment of one or more orifice units, as indicated in Fig. 9, attached to the outlet of the blowoff valve gives pressure reduction in easy stages so that the steam is eventually discharged at low pressure, thus avoiding the difficulties mentioned. The arrangement operates as a muffler or silencer and prevents injurious vibration. Under the principles as already explained the orifices are readily selected or designed to meet any given requirements. Another advantage in the combination is that the rate of flow through the orifice system, being practically constant for a given boiler pressure, gives a positive check on the amount of steam dis-

charged, and enables the same to be measured, under the principles already described.

The combination shown in Fig. 10 may be useful for several purposes. The threaded pipe 66 may lead from a steam engine exhaust, for example, or the drain from a superheater, to the series of orifice elements 12¹, the outlet from which is connected by a coupling 67 with a pipe 68 extending downwardly to a return bend 69, from which extends an uptake 70. This arrangement may afford a seal preventing back flow of vapor. The pipes 68 and 70 are shown broken away, indicating that they may be indefinitely elongated. At the top of uptake 70 is shown a T 71 from which extends upwardly a pipe 72 to the atmosphere and laterally an elbow 73, with a downtime therefrom to a hot well or elsewhere.

The Fig. 8 combination may be used for direct reading of flow of dry saturated steam per hour, by employing an orifice of approximate area .01944 sq. in. and shifting the dial pointer upwardly to the extent of 14.7 units so as to indicate absolute pressure; whereupon the ordinary calibration of the dial shows the steam flow in pounds per hour. With a different gas another orifice area will give a similar result. By taking an orifice of an area a multiple of that stated, the gage indication will show flow by multiplying by the same factor.

The following reservations of rights are indicated. The combination of an orifice system, as that in Fig. 1 or otherwise, with a relief valve, feed valve, or pump or any other regulator of flow, controlled by the pressure in the orifice system, or changes of such pressure, is not herein claimed but is made the subject of claim in copending applications, Serial Nos. 670 and 671, filed Jan. 5, 1925. The use of such orifice system, per se, as a liquid relief apparatus, without a separate regulator controlled by it, is made the subject of divisional application, Serial No. 302,025, filed August 25, 1928. The embodiments of Figs. 6, 7 or 8, or analogous forms, used as flow meters, are not claimed herein, but are made the subject of claim in copending application, Serial No. 120,691, filed July 6, 1926. The use of an orifice system as a muffler, or a pressure reducer, as in Figs. 9 or 10, or otherwise, is not herein claimed, but is made the subject of claim in copending application Serial No. 119,929, filed July 1, 1926.

It will thus be seen that there has been described an orifice element, a system or assemblage containing the same, and apparatuses utilizing such orifice element or system, embodying the principles and attaining the objects of the present invention. Since many matters of operation, combination, arrangement, structure and detail may be variously modified without departing from

the principles involved it is not intended to limit the invention to such matters except so far as specified in the appended claims.

What is claimed is:

- 5 1. An orifice element adapted to be interconnected with other elements of fluid flow apparatus, and consisting of a hollow vessel forming a walled chamber having entrance and exit openings and of bulging form between the openings to give large capacity to the orifice chamber, an orifice piece with constantly open orifice of fixed and scientifically predetermined effective area and so arranged that fluid traversing said openings must traverse the orifice, and coupling means at both the entrance and exit openings, one being exterior and the other interior of the walls of the vessel, and complimentary to each other, whereby the element may be coupled to a similar element or other fluid flow apparatus.
- 10 2. An orifice element adapted to be interconnected with other elements of fluid flow apparatus, and consisting of a hollow vessel forming a walled chamber having entrance and exit openings, an orifice nozzle so arranged that fluid traversing said openings must traverse the orifice, and coupling means at both the entrance and exit openings consisting of an interiorly threaded portion at one opening and an exteriorly threaded portion at the other opening, the two corresponding whereby identical elements can be directly coupled in tandem.
- 15 3. An orifice element adapted to be interconnected with other elements of fluid flow apparatus, and consisting of a hollow vessel forming a walled chamber having entrance and exit openings, an orifice nozzle so arranged that fluid traversing said openings must traverse the orifice, and coupling means at both the entrance and exit openings consisting of interior threads at one opening, and a cylindrical portion at the other opening with exterior threads corresponding to said interior threads, and interior threads

for removably receiving and holding said orifice nozzle.

4. An orifice element adapted to be interconnected with other elements of fluid flow apparatus, and consisting of a hollow vessel forming a walled chamber having entrance and exit openings, an orifice nozzle so arranged that fluid traversing said openings must traverse the orifice, and coupling means at both the entrance and exit openings, the vessel walls having one or more tapped apertures at a lateral point adapted to be closed by a plug or connected to other apparatus.

5. An orifice system adapted to be connected with other elements of fluid flow apparatus, comprising a plurality of separate orifice elements coupled together in tandem each orifice element consisting of a hollow vessel forming a walled chamber having entrance and exit openings, and with complementary coupling means at the respective openings, one being exterior and the other interior of the walls of the vessel, an orifice piece for each vessel so arranged that fluid traversing the system must traverse the orifices, a pressure pipe coupled to the entrance of the first orifice element, and a discharge pipe coupled to the exit of the last orifice element.

6. An orifice system comprising one or more orifice elements interconnected with other elements of fluid flow apparatus, and each consisting of a hollow vessel forming a walled chamber having entrance and exit openings, a plurality of orifice nozzles so arranged that fluid traversing said openings must traverse the orifices in succession and a pressure gage connected to one of said elements and in communication with the chamber between two orifices.

In testimony whereof, I have affixed my signature hereto.

GRANT CAMPBELL.
